DESIGN FOR A COMBINED SERVING BOWL AND DISH

Malcolm W. Lowenstein, Baltimore, Md.

Application April 1, 1941, Serial No. 100,072

Term of patent 14 years

To all whom it may concern:

Be it known that I, Malcolm W. Lowenstein, a citizen of the United States, residing in the city of Baltimore, State of Maryland, have invented a new, original, and ornamental Design for a Combined Serving Bowl and Dish, of which the following is a specification, reference being had to the accompanying drawing, forming a part thereof.

In said drawing:

Fig. 1 is a top plan view of the dish element of the combined serving bowl and dish;

Fig. 2 is a top plan view of the bowl element thereof; and

Fig. 3 is a perspective view of the combined serving bowl and dish in its assembled position, showing my new design.

I claim:

The ornamental design for a combined serving bowl and dish, as shown.

MALCOLM W. LOWENSTEIN.
